UNITED STATES PATENT OFFICE.

LEON GOLDBERG, OF NEW YORK, N. Y., ASSIGNOR TO VINCENT HORWITZ CO., INC., OF NEW YORK, N. Y., A CORPORATION OF NEW YORK.

DESIGN FOR A BEDROOM SLIPPER.

Application filed November 24, 1926. Serial No. 19,832. Term of patent 7 years.

To all whom it may concern:

Be it known that I, LEON GOLDBERG, a citizen of the United States, and a resident of New York city, borough of the Bronx, in the county of Bronx, State of New York, have invented a new, original, and ornamental Design for a Bedroom Slipper, of which the following is a specification, reference being had to the accompanying drawing, forming part thereof.

The drawing is a perspective view of a bedroom slipper showing my new design.

I claim:

The ornamental design for a bedroom slipper substantially as shown.

LEON GOLDBERG.
